US00D692901S

(12) **United States Design Patent**
Chung et al.

(10) **Patent No.:** US D692,901 S
(45) **Date of Patent:** ** Nov. 5, 2013

(54) **STAND FOR MONITOR**

(75) Inventors: **Yeon-Moo Chung**, Seoul (KR); **Jun-Pil Moon**, Seoul (KR)

(73) Assignee: **Samsung Electronics Co., Ltd. (KR)**

(**) Term: **14 Years**

(21) Appl. No.: **29/431,972**

(22) Filed: **Sep. 12, 2012**

(30) **Foreign Application Priority Data**

Jun. 26, 2012 (KR) 30-2012-0031066

(51) **LOC (9) Cl.** **08-07**

(52) **U.S. Cl.**

USPC **D14/451**

(58) **Field of Classification Search**

USPC D14/451, 452, 129, 209, 217, 224, 237, D14/238, 239, 432, 439, 447, 448; D8/349, D8/354, 355, 363, 373, 380; 248/176.1, 248/201, 205.1, 220.11, 284.1, 286.1, 248/309.1, 316.1, 323, 324, 349.1, 371, 248/398, 425, 917, 918, 919, 920, 921, 922, 248/923, 924, 121, 124.1, 127, 291.1, 313; 348/825, 827

(57) **CLAIM**

The ornamental design for a stand for monitor, as shown and described.

DESCRIPTION

FIG. 1 is a perspective view of stand for monitor, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a right side elevation reference view thereof in an alternative position, wherein the broken lines showing the stand for monitor with a monitor in an alternative position are for illustrative purposes only and form no part of the claimed design.

The broken-line disclosure in the views is to show environment and form no art of the claimed design.

1 Claim, 8 Drawing Sheets
